UNITED STATES PATENT OFFICE.

CHARLES W. BURKE, RICHARD J. RODGERS, AND JAMES D. PERKINS, OF ATLANTA, GEORGIA.

MAIL-BAG-EXCHANGE APPARATUS.

No. 922,665.

Specification of Letters Patent.

Patented May 25, 1909.

Application filed November 28, 1908. Serial No. 464,995.

To all whom it may concern:

Be it known that we, CHARLES W. BURKE, RICHARD J. RODGERS, and JAMES D. PERKINS, citizens of United States, residing at 5 Atlanta, in the county of Fulton and State of Georgia, have invented certain new and useful Improvements in Mail-Bag-Exchange Apparatuses, of which the following is a specification.

10 The primary object of the present invention is to provide novel, simple and inexpensive means for exchanging mail bags between moving trains and stations, said means effectively transferring the bags irrespective of their weight or the speed of the train, without danger of dropping said bags and without danger of injuring them.

A further object is to provide mechanism that can be employed irrespective of the direction of movement of the train and without the alteration of any part or parts, said mechanism being exceedingly simple.

Still another object is to provide mechanism which is adjustable with the track so 25 that in case the grade is changed by the workmen, the mechanism will still be in properly coöperative relation to the mechanism carried by the cars running on such track.

30 The preferred embodiment of the invention is illustrated in the accompanying drawings, wherein:—

Figure 1 is a front elevation of the track-side mechanism. Fig. 2 is a vertical sectional view therethrough and through a portion of a car having the coöperating mechanism thereon. Fig. 3 is a horizontal sectional view on line 3—3 of Fig. 2. Fig. 4 is an end elevation of the track-side mechanism. 40 Fig. 5 is a sectional view substantially on the line 5—5 of Fig. 2.

Similar reference numerals designate corresponding parts in all the figures of the drawings.

45 In the embodiment of the invention disclosed, the track-side mechanism is preferably mounted on ties 6 that are extended beyond the usual ties 7 of the railway track, these ties being secured to the rails in the ordinary manner. As disclosed two projecting ties are employed at each station, and mounted on the ends thereof are standards 50 8 supporting a casing 9. This casing includes a bottom 10, a roof 11, and a rear wall 12. The side, which faces the track, is

however open. Oppositely inclined inner walls 12^a are located within the casing and are joined to an upright 13, thus producing opposite open-ended bag-receiving pockets 13^a. The said inner walls are provided with 60 horizontal slots 15 having flared mouths 16, the walls of said slots being provided with wear plates 17.

The bags to be delivered to the trains are arranged in the space or recess formed between said inner walls 12^a, and to this end, a pair of oppositely swinging arms 18 are employed arranged to detachably engage rings 19 located on the ends of the bags. Positioning plates 20 are located in said recess on opposite sides of the slots and have their central portions cut away as shown at 21. The arms 19 as already stated are capable of swinging in opposite directions, but their movements are limited by brackets 22, said 75 brackets also serving as holding means for the inner walls 12^a.

The car-carried mechanism includes in its makeup a rock shaft 23 journaled, as shown at 24 on opposite sides of the door-way of 80 the car, said rock shaft extending across the doorway. This rock shaft has an inwardly extending handle 25 which can be yieldingly held in a horizontal position by a cable 26 secured to a spring 27 that is attached to the floor of the car. Outwardly divergent delivering and receiving arms 28 are secured to the rock shaft and terminate in inwardly extending hooks 29. These arms 28 are so arranged that when in a horizontal position they will pass through the slots 15 in the inner wall of the bag-receiving pockets.

90 The operation of the apparatus is substantially as follows. The mail bag 30 to be delivered from the car to the station is hung upon the rear arm 28, being fastened in place by a cord 31 that is easily broken. The bag 32 to be delivered from the station to the car is hung upon the arms 18, in which position it extends across the path of movement of said arms 28 as will be obvious. Assuming the parts arranged as disclosed in the drawings, it will be evident that as the forwardly extending arm 28 passes the station mechanism, it will enter the casing 9, and striking the central portion of the bag, will detach it from the arms 19. Said bag will follow along the arm 28 until it is caught in the confined space between the secured end of the arm 100 105 110

and the rock shaft. The rearwardly extending arm 28 carrying the bag 30, in turn passes through the casing, and said bag will enter the rear pocket 14. As it cannot pass 5 through the slot 12, it will remain in the pocket, the cords 31 being broken.

It will be evident that this structure is very simple, and there are a number of advantages for it. In the first place, there is no 10 danger of the bags dropping beneath the wheels of the train, with the consequent destruction of their contents. Then again, if the grade of the track is altered, inasmuch as the ties 6 must be changed, the track side 15 mechanism will always remain in proper co-operative relation to the car-carried mechanism. The apparatus is so arranged that it can be used irrespective of the direction of movement of the train, the bag to be transferred to the station being always placed upon the rear arm 28. It will thus be evident that these arms perform dual functions. When moving in one direction, one arm constitutes the bag-receiving device, but when 25 moving in an opposite direction, said arm acts as a delivering device.

From the foregoing, it is thought that the construction, operation and many advantages of the herein described invention will be 30 apparent to those skilled in the art, without further description, and it will be understood that various changes in the size, shape, proportion and minor details of construction may be resorted to without departing from

the spirit or sacrificing any of the advantages of the invention. 35

Having thus fully described our invention, what we claim as new, and desire to secure by Letters Patent, is:—

1. In mail bag exchange mechanism, the 40 combination with track-side mechanism, of car-carried mechanism, one of said mechanisms comprising oppositely disposed pockets having inner walls, delivering means located between the pockets and capable of swinging 45 in opposite directions, and means for limiting their swinging movements, said limiting means constituting holding means for the pocket walls.

2. In mail bag exchange mechanism, the 50 combination with track-side mechanism including oppositely disposed open-ended pockets having inner inclined walls provided with slots, of swinging arms located between the pockets for supporting a bag transversely 55 of said slots, and car-carried mechanism comprising a rock shaft having oppositely extending bag-delivering and receiving arms that pass through the pockets and through the slots in the inner walls thereof. 60

In testimony whereof we affix our signatures in presence of two witnesses.

C. W. BURKE.
R. J. RODGERS.
J. D. PERKINS.
